SLIP COVER FOR CYLINDRICAL CONTAINERS

Leon E. La Bombard, Fulton, N. Y., assignor to
Oswego Falls Corporation, Fulton, N. Y., a corporation of New York

Application December 12, 1934, Serial No. 757,166

2 Claims. (Cl. 229—5.5)

This invention relates to slip covers for fibrous containers of the type that are secured to the open end of the container by frictional contact with the outer wall of the container.

5 The general object of the invention is a slip cover provided with means readily operable to permit the slip cover to be quickly and conveniently removed from the container.

10 The fibrous container comprehended by this application is usually formed of a paper material, and the use of such containers has become universal, particularly, in connection with the sale of merchandise from retail stores, where the merchandise is transferred in bulk state to the 15 container by hand, as for example, these containers are used in soda fountains for hot and cold liquids, and ice-cream, and the like.

15 Slip covers for such containers usually comprise a disk provided with a depending annular flange. The disk portion rests upon and forms a closure for the open end of the container, and the depending flange fits snugly around the outer wall of the container adjacent the open end thereof. Usually no specific fastening means is 20 used to secure the cover to the container, it being held on the container solely by the friction between the depending flange portion of the slip cover and the side wall of the container. Accordingly, it is necessary to form the depending flange portion of the slip cover, or at least a portion thereof, of such dimensions, or of such 25 diameter, that it fits snugly on the open end of the container. Otherwise, a sufficiently tight seal will not be established between the slip cover 30 and the container. On account of the necessarily tight fit between the slip cover and the container, two problems are presented. First, pushing the slip cover onto the container and second, removing the slip cover from the container. This 35 invention has only to do with the second problem.

This problem, that is, the removal of the slip cover, exists particularly when the container is used for merchandise having gummy, or sticky, qualities, such as ice-cream, and also in connection 40 with the use of the container for hot drinks. After the hot liquid cools, a considerable vacuum is created in the top of the container. On account of this, and together with the fact that the cover is originally of a tight fit, a considerable 45 pull must be exerted to remove the cover. This often results in spilling the contents of the container, or otherwise mutilating the cover, so that it can not be conveniently put back onto the container.

50 The invention consists in the novel features

and in the combinations and constructions hereinafter set forth and claimed.

In describing this invention, reference is had to the accompanying drawings in which like characters designate corresponding parts in all 5 the views.

Figure 1 is a fragmentary, side elevation of the slip cover and contiguous portion of the container, partially in section.

Figure 2 is a fragmentary, sectional view taken 10 on line 2—2, Figure 1.

Figure 3 is a fragmentary, side elevation of a slip cover and contiguous portion of the container showing a modification of the invention.

Figure 4 is a fragmentary, sectional view taken 15 on line 4—4, Figure 3.

Figure 5 is a fragmentary, side elevation of a slip cover and contiguous portion of the container in section showing a modification of the structure shown in Figure 1.

Figure 6 is a fragmentary, sectional view taken 20 on line 6—6, Figure 5.

The side wall 10 of the cylindrical container is usually formed of one or more layers of paper material.

25 11 designates the disk portion of the slip cover which, as here shown, is provided with an upwardly 30 standing annular flange 12. The disk 11 is secured to a depending annular flange portion 35 13 in any suitable manner, as by crimping of the adjacent portions of the flanges 12, 13, as at 14. Usually, the slip cover is so formed that the internal diameter of the flange 13 is slightly less than the outside diameter of the container wall 10. The slip cover is placed upon the open end 35 of the container by pushing the flange 13 axially of the container and over the outer upper portion of the wall 10.

40 Referring to Figures 1 and 2, the flange 13 is formed with a flap 15 defined by the upwardly 40 extending cuts or incisions 16, and horizontal cut 17. The flap may be of any desired shape, but preferably the top cut 17 is located a short distance below the disk 11, and extends circumferentially of the flange 13, as indicated in Figure 2. 45 The portion 20, above the tab 15, provides a continuous sealing surface against the upper portion of the wall 10 of the container.

The incisions 16 and 17 are preferably cut at an angle to the surface of the flange 13, as indicated 50 at 21, Figure 2, the incisions being cut at an angle so as to resist outward movement of the flap 15 beyond the peripheral surface of the flange 13.

In removing the slip cover from the container, the flap 15 is pressed inwardly by the thumb or 55

finger, as indicated in Figure 2, which in turn presses the contiguous portion of the side wall 10 inwardly in spaced relation relative to the flange 13, or the portion 20 thereof, permitting air to enter the upper portion of the container to relieve the vacuum, when the container has been filled with a hot liquid, and also reducing the friction between the container wall 10 and the flange 13 of the slip cover. The notch produced in the flange 13 by the inward movement of the flap 15 forms a convenient recess for the thumb, or finger nail, and thus provides a better grip with which to remove the slip cover.

In Figures 3 and 4, the flange 13 is provided with an incision or cut 22 extending circumferentially of the flange. The incision 22 is preferably spaced about the same distance from the disk portion 11 as is the incision 17 defining the top of the flap 15 but of comparatively greater length to permit that portion 23 of the flange 13 immediately below the incision 22 to be pressed inwardly without tearing, or mutilating, the flange 13.

As shown in Figure 4, the portion 23 of the slip cover, immediately below and centrally of the incision 22, is pressed inwardly producing substantially the same effect as that obtained by operation of the flap 15. It will be observed that in both instances the slip cover may be easily replaced on the container as no substantial damage is done to the flange 13 during the removal of the cover. Also, the incisions permit convenient escapement of the air from the container which results in an easier application of the cover to the container.

In instances where the slip cover becomes fixed, or set, on the container, as where the flange 13, or upper portion of the container, becomes moist over a period of time, or in instances where it is not desired to replace the slip cover after it has been removed, the flap 15 may be provided with a pull tab 25, as shown in Figures 5 and 6. The pull tab 25 may be secured to the flap 15 by any suitable means such as a staple 26. With this structure, the slip cover is removed by pulling 10 outwardly and then downwardly on the tab 25, which action swings the upper portion of the flap 15 outwardly and then severs the flange 13 immediately below the flap 15, thereby permitting ready removal of the slip cover. 15

What I claim is:

1. A slip cover for fibrous containers comprising a disk portion, a depending annular flange secured to the disk portion and arranged to snugly fit the upper end of the container, an incision 20 extending through the flange of the cover, the incision being arranged between the bottom of the disk portion and the lower edge of the flange, and being formed at an angle relative to the peripheral surface of the flange so as to resist outward movement of the flange below the incision beyond the peripheral surface of the portion of the flange above the incision. 25

2. A slip cover for fibrous containers including a disk portion, a depending annular flange 30 portion, a plurality of incisions extending through said flange and defining a hinged flap portion, said flap being provided with a pull tab.
